UNITED STATES PATENT OFFICE

MALCOLM HAIN, OF MONTCLAIR, NEW JERSEY

SPINNING FRAME

Application filed March 19, 1930. Serial No. 437,032.

This invention relates to spinning and kindred machines in which the wound packages are arranged in rows at different elevations and there is provision for causing said rows to change places, for instance, so that when the bobbins or equivalent cores of one row (as the upper row) in the working position have become filled they will be replaced by the empty ones of the other row and will themselves assume the position for doffing.

My object is to provide a machine of this class wherein the interchange of positions of the two rows of packages may be accomplished by mechanism more simple and reliable than heretofore and by an operation easily performed by the attendant. To this end each carrier for each row of packages is rotative on a substantially horizontal axis in and eccentric with reference to the axis of a structure itself movable around a substantially horizontal axis and there is means as said structure is moved to cause the carrier to rotate therein so that as it changes from one elevation to another it will in both positions face in substantially the same direction—so that the packages thereon will project upwardly in both positions. In the preferred form the said structure and each carrier are connected by planetary gearing. The invention further contemplates maintaining the carriers facing in said direction even though, when the spinning or other operation is proceeding, the carriers undergo reciprocation relatively to yarn fliers or equivalent guides.

In the drawings,

Fig. 1 is a side elevation of a spinning machine embodying one form of the invention;

Fig. 2 a front elevation thereof;

Fig. 3 a front-to-rear vertical section immediately at the right of arm 3^a in Fig. 2;

Fig. 4 a front elevation of a spinning machine embodying another form;

Fig. 5 a section on line 5—5, Fig. 6;

Fig. 6 a front-to-rear vertical section immediately at the left of the right-hand frame gable in Fig. 4;

Fig. 7 is a section on line 7—7, Fig. 6;

Fig. 8 a modification of holding means for the rotary bobbin-rail-including system;

Fig. 9 is a front elevation of the machine embodying another form;

Fig. 10 is a section immediately to the left of the right-hand shifter in Fig. 9; and

Fig. 11 a section on line 11—11, Fig. 9.

A supporting means is afforded by the frame 1 and supports 3 arranged to slide up and down on guides 2 and having counterweights 4 connected thereto by chains 5 which extend up over sprocket wheels 6 on a horizontal shaft 7 which may be oscillated by any suitable means (not shown) connected to a crank or cranks 8 thereon so as to produce, as will appear, the necessary traverse as between the yarn and yarn packages. 9 designates the fliers and 9^a a belt and pulley means for rotating them.

Figs. 1 to 3: On the arms 3^a of the supports 3 are fixed pinions 10 and coaxial therewith and journaled in said arms are the shafts 11 of a two-part shiftable (here rotative around the axes of said shafts) structure each part of which comprises, with a shaft 11, disks 12 and 13 fixed to said shaft one each side of each arm. Diametrically opposite pinions 14 are fixed on shafts 14^a journaled in disks 12 and these are connected with the fixed pinions 10 by intermediate pinions 15 journaled in disks 12. The wound-package carriers are formed by the rails 16 having their end portions 16^a affixed to shafts 14^a. Thus the shiftable structure and the carriers form a planetary system. The carriers are arranged so that their package-supporting surfaces face alike or upward, and the described gearing is such that when the system comprising said shiftable structure and the carriers is rotated a half cycle the carriers again face upwardly. 17 designates bobbins forming the cores of the packages and seated on the carriers, those on each carrier in front-to-rear planes operatively coinciding with the fliers so as that each row will cooperate therewith when it is up.

The means for shifting said planetary system to cause the two carriers to change places when doffing and replenishment of the bobbins are to be done—here also designed to

5 maintain said system against turning in the interim—is as follows: A rotary shifter 18, journaled in the end gable 1^a of the frame coaxially with said system, has a diametric inside rib 18^a formed with a slot 18^b receiving a pair of diametrically opposite studs 19 on the adjoining disk 13 of said system. This shifter may be held against rotation by the pull-out pin 20 engageable in either of 10 two diametrically opposite holes (not shown) in the shifter. The shifter has a gear 18^c with which meshes a pinion 21 journaled in the gable and having a crank 21^a by which to rotate it and hence said shifter and system. To intercouple the two parts of the 15 aforesaid shiftable structure the shifter may be duplicated and the two shifters connected by a rotary shaft 18^x having pinions 18^y meshing with their gears 18^c.

20 The drawings show the up-and-down reciprocated mechanism comprising the counterbalanced supports and said rotary system depressed in position for rotary shifting of said system, which may be then accomplished by withdrawing the keeper and turning crank 21^a. At this time said mechanism is somewhat below its lowest limit of traverse during spinning so that the bobbins as 25 shifting will clear the fliers, accomplished as 30 by disconnecting the means for oscillating shaft 7. When said mechanism has been reconnected to said means, and then elevated to position for traverse, the spinning operation proceeds in the regular way, said system being kept from rotative shifting by its engagement in the slots of the shifters now locked by the keeper. When said system occupies either of the two positions in which it is 35 locked by the keeper the arrangement of the carriers is preferably such that the upper carrier is back of the lower to afford clearance 40 for doffing.

45 Figs. 4 to 8: In this form the rotary system has the carriers movable planetarily as in the form already described, but such motion is intermittent; this form also differs in that the means for rotarily shifting the rotary system and for maintaining said system against turning while actual spinning is 50 going on are contained in said mechanism itself and partake of its traverse motion. Each support 22 here includes an internally grooved annulus 22^a in whose groove is revolute an annular gear 23 forming one of 55 the parts of the two-part shiftable structure. In each gear are journaled the diametrically opposite shafts 24 to which are affixed the end portions 25^a of the two bobbin rails 25, one such shaft having a star wheel 26 whose 60 equally spaced notches 26^a are adapted to receive equally spaced studs 27 on the annulus, whereby to rotate in said shiftable structure intermittently each carrier 24—25—26 thus formed when said structure is rotated. 65 When the system including said structure

70 and the carriers is in that position (Fig. 6) in which the upper carrier is back of and thus affords clearance to the lower row of bobbins 28 for doffing the parts are held against turning by spring-pressed pins 29 arranged in gears 23 and adapted to engage 75 equally spaced notches 24^a in shafts 24. Or said parts may be held against turning by providing (Fig. 8) on each or both of the shafts 24 of each carrier a faceted block 30 whose facets may successively move in wiping contact with the surface of annulus 22^a as in the rotation of the system each carrier is rotated, clearance being afforded the angles or corners of the block by recesses 22^b in said annulus. The rotation of said system is in the form now being described effected by rotating, by crank 31^a, a shaft 31 having pinions 32 meshing with gears 23.

80 The mechanism in this form may be guided and reciprocated vertically when spinning is proceeding the same as in the first form; and when rotary shifting of said system is to be effected for doffing and replenishment of the bobbins said mechanism is first lowered as 85 already described to clear the upper packages from the fliers.

85 Figs. 9 to 11: In this case the supports 33, the shiftable structure formed by annular gears 34, and the carriers 35 are the same as 90 in Figs. 4 to 7, but the movement of the carriers planetarily is effected by arms 36 one of 95 which is keyed to the shaft 35^a of each carrier and each having a longitudinal slot 36^a receiving a stud 37^a on an arm 37 of the support. For interchanging the positions of the carriers there is the same shifting mechanism as in Figs. 1 to 3, to wit, the shifters 38 journaled in the frame coaxial with the planetary system 34—35 (when the mechanism is 100 depressed) and having their slots 38^a receiving the ends of the carrier shafts, the rotary shaft 39 having pinions 40 meshing with the gears 38^b of the shifters, the pinion 41 meshing with one gear 38^b and having the crank 41^a for effecting the shifting, and the pull-out pin 42 for holding the shifter mechanism 105 against turning when the spinning is going on. The control of the planetary system 34—35 to prevent it from rotary displacement when the mechanism is being traversed is completed by the slotted extension members 43 affixed to the frame.

110 Having thus fully described my invention what I claim is:

1. In combination, supporting means, a shiftable structure movable therein around a substantially horizontal axis, carriers for the wound packages movable in said structure around substantially horizontal axes arranged in different radii extending from the first axis, and means to cause each carrier to rotate in said structure and thereupon face a given direction each time said carrier in its 115 120 125 130

- movement with said structure occupies a given position.
2. In combination, supporting means, a shiftable structure movable therein around a substantially horizontal axis, carriers for the wound packages movable in said structure around substantially horizontal axes arranged in different radii extending from the first axis, and means, connecting each carrier with the supporting means, to cause such carrier to rotate in said structure and thereupon face a given direction each time said carrier in its movement with said structure occupies a given position.
3. In combination, supporting means, a shiftable structure movable therein around a substantially horizontal axis, carriers for the wound packages movable in said structure around substantially horizontal axes arranged in different radii extending from the first axis, and means to cause the carriers to rotate in said structure and thereupon face a common direction each time said carriers in their movement with said structure occupy given positions.
4. In combination, supporting means, a shiftable structure movable therein around a substantially horizontal axis, carriers for the wound packages movable in said structure around substantially horizontal axes arranged in different radii extending from the first axis, and means, connecting each carrier with the supporting means, to cause the carriers to rotate in said structure and thereupon face a common direction each time said carriers in their movement with said structure occupy given positions.
5. In combination, supporting means, a shiftable structure movable therein around a substantially horizontal axis in a given direction, carriers for the wound packages movable in said structure around substantially horizontal axes arranged in different radii extending from the first axis, and means to cause each carrier in its movement with said structure through a given number of degrees to rotate in the relatively opposite direction through substantially the same number of degrees.
6. In combination, supporting means, a shiftable structure movable therein around a substantially horizontal axis in a given direction, carriers for the wound packages movable in said structure around substantially horizontal axes arranged in different radii extending from the first axis, and means, connecting each carrier with the supporting means, to cause each carrier in its movement with said structure through a given number of degrees to rotate in the relatively opposite direction through substantially the same number of degrees.
7. In combination, supporting means, a shiftable structure movable therein around a substantially horizontal axis, a wound pack-
- age carrier movable in said structure around a substantially horizontal axis arranged eccentrically of the first axis, and means to cause the carrier to rotate in said structure and thereupon face a given direction each time said carrier in its movement with said structure occupies a given position.
8. In combination, supporting means, a shiftable structure movable therein around a substantially horizontal axis, a wound package carrier movable in said structure around a substantially horizontal axis arranged eccentrically of the first axis, and means, connecting the carrier with the supporting means, to cause the carrier to rotate in said structure and thereupon face a given direction each time said carrier in its movement with said structure occupies a given position.
9. In combination, supporting means, a shiftable structure movable therein around a substantially horizontal axis in a given direction, a wound package carrier movable in said structure around a substantially horizontal axis arranged eccentrically of the first axis, and means to cause the carrier in its movement with said structure through a given number of degrees to rotate in the relatively opposite direction through substantially the same number of degrees.
10. In combination, supporting means, a shiftable structure movable therein around a substantially horizontal axis in a given direction, a wound package carrier movable in said structure around a substantially horizontal axis arranged eccentrically of the first axis, and means, connecting said carrier with the supporting means, to cause the carrier in its movement with said structure through a given number of degrees to rotate in the relatively opposite direction through substantially the same number of degrees.
11. In combination, supporting means, and a planetary system comprising a shiftable structure movable in said means around a substantially horizontal axis and carriers for the wound packages movable in said structure around substantially horizontal axes arranged in different radii extending from the first axis and intergeared with said structure.
12. In combination, supporting means, and a planetary system comprising a shiftable structure movable in said means around a substantially horizontal axis in a given direction and carriers for the wound packages movable in said structure around substantially horizontal axes arranged in different radii extending from the first axis and intergeared with said structure to move relatively reversely thereto.
13. In combination, supporting means, and a planetary system comprising a shiftable structure movable in said means around a substantially horizontal axis and a wound package carrier movable in said structure.

around a substantially horizontal axis arranged eccentrically of the first axis and intergeared with said structure.

14. In combination, supporting means, and a planetary system comprising a shiftable structure movable in said means around a substantially horizontal axis and a wound package carrier movable in said structure around a substantially horizontal axis arranged eccentrically of the first axis and intergeared with said means.

15. In combination, supporting means, and a planetary system comprising a shiftable structure movable in said means around a substantially horizontal axis and a wound package carrier movable in said structure around a substantially horizontal axis arranged eccentrically of the first axis and intergeared with said structure to move relatively reversely thereto.

16. In combination, a frame, an up-and-down reciprocatory support therein, a shiftable structure movable in the support around a substantially horizontal axis, a wound package carrier carried by said structure, and means in the frame for confining said structure against movement in said support while reciprocating therewith.

17. In combination, a frame, an up-and-down reciprocatory support therein, a shiftable structure movable in the support around a substantially horizontal axis, a wound package carrier carried by said structure, and means in the frame for confining said structure against movement in said support while reciprocating therewith, said means being movable and in a given position of the support adapted to move said structure around said axis.

18. In combination, a frame, an up-and-down reciprocatory support therein, a planetary system comprising a shiftable structure movable in the support around a substantially horizontal axis and a wound package carrier movable in said structure around a substantially horizontal axis and intergeared with said structure, and means in the frame for confining said structure against movement in said support while reciprocating therewith.

19. In combination, a frame, an up-and-down reciprocatory support therein, a shiftable structure movable in the support around a substantially horizontal axis, a wound package carrier carried by said structure, and means in the frame for confining said structure against movement in said support while reciprocating therewith, said means being movable and in a given position of the support adapted to move said structure around said axis.

In testimony whereof I affix my signature.

MALCOLM HAIN.
